US0D1061347S

(12) **United States Design Patent** (10) **Patent No.:** **US D1,061,347 S**
(45) **Date of Patent:** **** Feb. 11, 2025**

(54) **BICYCLE PEDAL**

(71) Applicant: **Wahoo Fitness L.L.C.**, Atlanta, GA (US)

(72) Inventor: **David R. Buenger**, Roswell, GA (US)

(73) Assignee: **Wahoo Fitness L.L.C.**, Atlanta, GA (US)

(**) Term: **15 Years**

(21) Appl. No.: **29/879,308**

(22) Filed: **Jul. 6, 2023**

Related U.S. Application Data

(63) Continuation of application No. 29/773,172, filed on Mar. 8, 2021, now Pat. No. Des. 999,122.

(57) **CLAIM**

The ornamental design for a bicycle pedal as shown and described.

DESCRIPTION

FIG. 1 is a top-front perspective view of a bicycle pedal embodying my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines in the figures show portions of the bicycle pedal that form no part of the claimed design.

1 Claim, 4 Drawing Sheets
